RECLINING AND ADJUSTABLE CHAIR FOR INVALIDS

Richard L. Vance, Franklin, N.C., assignor to Macon Program for Progress, Inc., Franklin, N.C., a corporation of North Carolina

Filed July 31, 1967, Ser. No. 8,071

Term of patent 14 years

(Cl. D15—1)

FIG. 1 is a view in perspective looking at the left side and front of a reclining and adjustable chair for invalids embodying my new design;

FIG. 2 is a view in perspective looking at the right side and front of the chair as shown in FIG. 1;

FIG. 3 is a view in perspective looking at the right side and rear of the chair as shown in FIG. 1;

FIG. 4 is a view in perspective looking at the left side and front of the chair shown in FIG. 1 but adjusted to the reclining position and with the tray removed.

I claim:

The ornamental design for a reclining and adjustable chair for invalids, substantially as shown and described.
